INVENTOR
Isaac H. Hellman.

By Ralph Koenig
ATTORNEY

UNITED STATES PATENT OFFICE.

ISAAC H. HELLMAN, OF ST. LOUIS, MISSOURI.

CONTAINER.

Application filed January 14, 1924. Serial No. 686,073.

To all whom it may concern:

Be it known that I, ISAAC H. HELLMAN, a citizen of the United States, residing at the city of St. Louis, State of Missouri, have 5 invented a certain new and useful Improvement in Containers, of which the following is a specification, reference being had to the accompanying drawing, forming a part thereof.

10 This invention relates generally to containers and, more particularly, to a certain new and useful improvement in containers of the tube type especially adapted for tooth-paste, shaving-cream, medicinal salves, and 15 the like.

My invention has for its chief object the provision of a container of the type stated and its stopper-cap with spring means for conjointly so fastening or securing the cap 20 and container together that the cap may be freely seated in closing position upon or removed from the container and upon removal is yieldingly swung laterally or transversely away from the mouth of the container and supported conveniently at hand 25 for ready replacement.

With the above and other objects in view, my present invention resides in the novel features of form, construction, arrangement, 30 and combination of parts hereinafter described and afterwards pointed out in the claim.

In the accompanying drawing,

Figure 1 is a fragmental elevational view 35 of a container and its stopper-cap embodying my invention;

Figure 2 is a plan view of the same.

Referring now more in detail and by reference characters to the drawing, which illustrates a preferred embodiment of my invention, 1 designates a container of preferably standard collapsible tube form or type especially adapted for shaving-cream, tooth-paste, medicinal salves, and the like. 40

45 At its upper end, tube 1 is reduced, as at 2, and centrally provided with an outlet-neck 3 externally threaded, as at 4, and formed with a circumferential groove or recess 5.

50 Adapted to seat on neck 3 and internally threaded for detachable or removable en-

gagement with its threads 4, is a stopper-cap 6 formed or provided with a circumferential groove 7.

8 designates a cap-attaching member, 55 which is preferably constructed of spring-wire, and which is looped upon itself and permanently seated at one end, as at 9, in the groove 5 of the container-neck 3 and similarly looped upon itself and permanently seated at its other end, as at 10, in the groove 7 of cap 6, the permanent engagement between the member 8 and either or both the neck 3 and cap 6 being of such looseness as to allow relative freedom for rotatory movement between the container 1 and cap 6 in both threading the cap in closing position upon the container or in unthreading the cap for removal from the container to permit emission of the container-contents. 70

Intermediate its opposite ends 9 and 10, the member 8 is coiled upon itself, as at 11, longitudinally of the container 1, or, as it may be said, substantially horizontally relatively to the cap 6, as shown, so that, when 75 the cap 6 is unseated or removed from the neck 3, the member 8 will resiliently carry or swing the cap 6 transversely or laterally to one side of neck 3, as indicated by dotted lines in Figure 2. Interference with proper 80 emission of the container-contents is thus efficiently avoided, and yet the cap 6 is supported upon the container in such manner as to be conveniently ready at hand for replacement in closing position upon the container. 85

My new cap-fastening means is simple and inexpensive in form and construction and is exceedingly efficient in the performance of its intended functions. 90

I am aware that minor changes in the form, construction, arrangement, and combination of the several parts of my new container and its cap-fastening means may be made and substituted for those herein shown and described without departing from the nature and principle of my invention. 95

Having thus described my invention, what I claim and desire to secure by Letters Patent is:

A container comprising a receptacle having an outlet neck, a removable stopper cap

for engagement with said outlet neck, and a spring device comprising a portion connected to said outlet neck; a portion connected to said stopper cap, and a coil spring 5 connecting said portions, said coil spring being horizontally disposed relatively to the stopper cap and the outlet neck and

under tension when the stopper cap engages the outlet neck whereby said stopper cap is resiliently urged away from the outlet neck when disengaged therefrom. 10

In testimony whereof, I have signed my name to this specification.

ISAAC H. HELLMAN.
